UNITED STATES PATENT OFFICE.

PERCY A. BOECK, OF WORCESTER, MASSACHUSETTS, ASSIGNOR TO NORTON COMPANY, OF WORCESTER, MASSACHUSETTS, A CORPORATION OF MASSACHUSETTS.

ELECTRIC FURNACE.

1,158,972.

Specification of Letters Patent.

Patented Nov. 2, 1915.

Application filed November 2, 1911. Serial No. 658,092.

To all whom it may concern:

Be it known that I, PERCY A. BOECK, a citizen of the United States, residing at Worcester, in the county of Worcester and 5 State of Massachusetts, have invented certain new and useful Improvements in Electric Furnaces, of which the following is a specification.

This invention relates to electric resistance furnaces, or analogous constructions such as electric heaters, rheostats or the like, the objects of the invention being the provision of an improved construction of this type, and particularly of an improved electric furnace in which the heat is efficiently applied and utilized.

For a full understanding of the invention reference is made to the accompanying drawings illustrating one embodiment 20 thereof.

The particular form of furnace chosen for illustration of the principles of the invention is a tube-furnace, but it is to be understood that the principles are equally applicable to the construction of other types of electric furnaces or electric-furnace elements, as for example muffle or crucible furnaces, heating or resistance elements, and the like.

30 In the drawings, the figure is a central longitudinal section, the central portion being broken away.

1 represents a tube or core of highly refractory material of high thermal conductivity, this tube constituting the support for the resistance element. As illustrated the tube 1 is provided with an external helical groove 2, in which the resister 3 is coiled. The resister may comprise a wire of nickel-chromium alloy, platinum, or other suitable material, and is preferably formed, before being wound upon the core or support, into a continuous coil or helix, which is then wound in the groove 2 in the manner indicated. This construction presents the particular advantages that the length of the resister can be increased to any necessary extent, while at the same time the liability of breakage is minimized. The support 1 should be of a material which in addition to the necessary refractory character possesses high thermal conductivity. Suitable materials for the purpose are previously molten alumina grains bonded by fritting

together or by the use of a small proportion of a ceramic or basic bond; and silicid of carbon, bonded by re-crystallization or otherwise.

The core, with the resistance element wound thereon, is filled and covered with a substantial layer of refractory cement 4, and the whole is covered by a casing 6, which may be of iron. Between the refractory cement 4 and the casing 6 is a filling 5, preferably consisting of pounded magnesia and constituting an electrical and thermal insulator. As illustrated by way of example, the refractory covering 4 is formed with end flanges 4^a which support the casing 6 and retain the filling 5. The terminals 3^a of the resister 3 extend outwardly through apertures 7 in the casing 6 in position for connection to the external circuit.

8 represents a removable cover, which may consist of the same material as the core 1. It is to be understood that the details of construction above described are illustrative only.

The refractory cement or composition 4 which covers the resistance element 3 is composed of grains of previously molten alumina, in conjunction with a relatively small proportion, say 5 to 15 per cent. or somewhat more, of a suitable bond, as for example a plastic clay, or lime or magnesia. A composition of this character presents very important technical advantages for use in this connection: in particular it is chemically inactive with respect to the resister and preserves the wire from corrosion; and by reason of its high thermal conductivity, greatly exceeding that of porcelain, fire-clay or the like, it conducts the heat rapidly from the resister, thereby preventing general or localized overheating and consequent injury. At the same time it aids in the even distribution of heat throughout the core. Furthermore, by reason of the high specific heat of the cement it is adapted to serve as a heat accumulator or equalizer, preventing unduly large fluctuations of the interior temperature when articles are introduced into or removed from the furnace, or when the covers are removed. It will be understood that a cement of this character may be used in connection with any desired type or core or support and resister.

In a furnace or heater constructed as herein described, the distribution of the resister is such as to provide a substantially even temperature within the chamber, while at the same time the coils or turns of the resister are firmly held. The walls in contact with the resister may be made very thin, and their thermal conductivity is such as practically to avoid danger of cracking or checking during rapid changes of temperature.

I claim:

1. In an electric furnace, a furnace chamber having walls of refractory material, a resistance element surrounding said wall, and a heat-distributing and heat-equalizing envelop comprising previously molten alumina, said envelop inclosing the resist-

ance element and serving to prevent general or local overheating thereof.

2. In an electric furnace, a furnace chamber having walls of refractory material, a resistance element surrounding said wall, a heat-distributing and heat-equalizing envelop comprising previously molten alumina, said envelop inclosing the resistance element and serving to prevent general or local overheating thereof, and a heat-insulating pack-
ing surrounding said envelop.

In testimony whereof I affix my signature in presence of two witnesses.

PERCY A. BOECK.
